J. OREM, Jr.

Making Axes.

No 9,000.

Patented Jun 8, 1852.

UNITED STATES PATENT OFFICE.

JOHN ORELUP, OF BALLSTON SPA, NEW YORK, ASSIGNOR TO ISAIAH BLOOD, AUG. J. GOFFE, AND GEO. R. THOMAS, OF BALLSTON SPA, NEW YORK.

PROCESS FOR MAKING AXES.

Specification of Letters Patent No. 9,000, dated June 8, 1852.

To all whom it may concern.

Be it known that I, JOHN ORELUP, of the village of Ballston Spa, Saratoga county, State of New York, have invented a new 5 and useful process for the manufacture of axes, together with the apparatus necessary for accomplishing the same, which I call "Orelup's process of ax making;" and I declare the following specification, with the 10 drawings forming part of the same, to be a full and accurate description thereof.

My improvement relates especially to the manufacture of that part called technically the ax-pole, that is the ax as it is forged 15 previous to the affixing to it of the steel edge. It has been usual before the date of my invention to make the poles of axes by taking a piece of iron of a proper size (according as the ax was intended to be large 20 or small) and hammer each end thin leaving it (the piece of iron) of its original thickness in the middle to form the head of the pole; then the two ends which have been reduced are bent at right angles to the 25 thick part where they join the same so that the straight side of the piece of iron forms the inside or eye of the ax and the shoulder formed by the thick part where it joins the thin, comes upon the outside and forms the 30 side of the pole; a piece of iron of a proper size (called a slug) is placed between the thin ends and to which they are welded. When made in this way the iron is very apt to break where the thin parts join the thick 35 and the labor is lost and the iron of little worth.

To remedy the defect above mentioned and effect as much at one heat as is effected at two by the old method I take a piece of 40 iron cut from a bar which has been rolled of the proper width and thickness for the particular size of the ax designed to be made. Such a piece of metal is shown in Figure 1^a. It is a little more than half 45 as thick, a little less than the width, and a little less than twice as long as the ax pole to be made. This bar is to be subjected to the operation of a trip hammer, having as its lower face a tool or die formed as 50 shown as Fig. 2^a, which is a perspective view of it as seen from below, and at Fig. 4^c where a cross section of it through the center is shown in a different perspective view of said face. From these views it will 55 be seen that the hammer-face or die consists

of a parallelepiped *a a a a*, with projecting or elevated ends *a, b*,—*a—c* separated by a space but a little larger than the intended width of the ax pole; a tongue or feather *d* connecting these elevated ends, along the 60 center of the face, and having its lower edge rounded. The ends *a b—a c* have all their edges also rounded. The tongue *f* on the top of the *a, a*, is for the purpose of attaching it to the trip-hammer when in use. 65

The operation with the hammer is as follows: Spaces having been determined toward each end of the bar at which to form half the eye for the ax, as at *i, i, i, i* Fig. 1; the bar is heated to a forging heat and laid 70 upon a flat anvil *B*, then blows are to be struck with the rounded ends *a, b* or *a, c* of the hammer, near and parallel with the edges of the bar at the spots *i, i, i, i*. The effect of these blows is to spread the iron 75 laterally at those spots, and give the bar the form shown at Fig. 3. The bar is then laid directly under the hammer so that the tongue *d* may operate directly upon the spaces *i i i i* marked out for the half-eyes, 80 when by rapid hammering each half eye is sunk in the metal at *m, m*, Fig. 4, which by the same operation is also drawn out so as to give the bar the shape shown at Fig. 5. The half eyes are completed and finished by 85 turning the bar over, and laying them alternately on the swaging tool, whose shape is shown with sufficient distinctness in Fig. 6 to make a more specific description unnecessary, when a few blows on the back of the 90 bar with a flat faced hammer finishes each half eye and makes them equal and similar. The bar is now cut across equidistant from the half eyes that is in the center of the bar nearly but not quite through, as from *x* to *y* 95 Fig. 5, upon the side opposite to that in which the half eyes have been sunk. It is then bent over or doubled in a direction the reverse of that heretofore practised, so that the portion uncut from *x* to *z* serves 100 for a hinge so that the half eyes come together and are opposite to and coincide with each other, as shown in Fig. 7 and so that the part hammered in making the score or half eye comes inside (instead of outside 105 as in the old method) and the halves of the ax pole are now ready to be welded together the two faces of the score *x y* forming the face of the head as *x y x y* Fig. 7. The welding being done the process is completed 110

and the pole is ready to receive the steel edge which finishes the ax.

- The following may be enumerated as the advantages I claim to be effected by the above process: 1. The eye is made symmetrical, and also similar in all axes of the same class, leaving the thickness of the ax on each side of the eye equal. 2. The cutting of the ax head partially through and then 10 turning over the metal, permits the making of a more finished article with less labor than by the usual method of turning the metal over in a loop, and hammering it down to shape. 3. The whole process can be accomplished in one heating of the metal, which cannot be done by the ordinary process. The result of the whole being that a more perfect and a cheaper article is produced than by the common processes. 15 20 I claim the method of manufacturing ax poles by a process of which the following are its successive steps in combination with others, as they are applied to the metal bar

when heated and prepared for manufacture viz.—

25

1. Spreading the iron bar at four points on its edges by strokes of a peculiar tool made for the purpose.
2. Forming half-eyes across the bar at spaces equi-distant from its center, by 30 strokes of a narrow and round edged hammer.
3. Finishing the half eyes and making them equal and similar on a swaging tool.
4. Cutting the bar partly through across 35 its center and doubling together the halves of the bar so that the half-eyes shall unite in correspondence with each other and form the eye of the ax, completing the whole ready for welding the two halves of the pole 40 together, substantially as the process is set forth in the above specification.

JOHN ORELUP.
